UNITED STATES PATENT OFFICE

HAROLD F. ELLIOTT, OF PALO ALTO, CALIFORNIA, ASSIGNOR, BY MESNE ASSIGNMENTS, TO RADIO CORPORATION OF AMERICA, OF NEW YORK, N. Y., A CORPORATION OF DELAWARE

STABILIZED AMPLIFIER SYSTEM

Application filed October 10, 1928. Serial No. 311,491.

This invention relates to electronic emission amplifiers, and especially to the use of such amplifiers to amplify high frequency and audio frequency alternating currents, such as encountered in radio reception, and in the reproduction of sound.

The electronic emission amplifier for these purposes usually includes an evacuated vessel, in which several electrodes are enclosed. Thus there is an electronic emission electrode, in the form usually of an electrically heated filament or cathode; as well as a plate or anode on which the electrons are received. By the aid of an external source of potential, the anode is kept positive as regards the cathode, and when this is done, a considerable "space current" can flow through the tube space, the circuit being completed through the external connection between the anode and the cathode.

It has been found that the quantity of electron flow between these two electrodes can be easily controlled by providing an electrode in the tube space, the potential of which can be varied with reference to the cathode. This control electrode is usually in the form of a grid. If variations in potential difference exist between the cathode and this grid, as for example those due to the signaling impulses to be amplified, then corresponding variations in the space current result. It is this feature that has been utilized for the amplification function. The magnified current variations can be impressed on an impedance or transformer, and the resultant variations in potential difference can, if desired, be again amplified by a succeeding stage.

Such amplifiers operate efficiently and without serious drawbacks when only nominal amplification is attempted, but when the degree of amplification is high, as in cascade amplification, there are effects that disturb the successful operation of the system. These may be due to the inherent capacity couplings between the tube electrodes, which although minute produce appreciable results when several stages of amplification are used. Due to these capacity couplings, the output circuit reacts in the input circuit, and

succeeding stages of amplifiers react on preceding stages. These reactions lead to the formation of oscillations which may be of several types. If the amplifier employs tuned circuits, as is frequently done in amplification at radio frequencies, oscillations may be formed at the frequency to which the circuits are tuned. Various neutralizing systems have been devised to overcome this form of oscillations. However, the means which are employed for neutralizing frequently aggravate another form of instability, and lead to the generation of parasitic oscillations whose frequency depends upon the stray capacitances and leakage inductances of the system. These parasitic oscillations may be so strong as to render the amplifier entirely inoperative.

Substantially similar parasitic effects are noted in connection with push-pull amplifiers, used either for radio or audio frequencies. Such push-pull systems have leakage inductances and stray capacitances forming circuits resonant at high frequencies, and therefore especially prone to sustain such oscillations.

It is one of the objects of my invention to correct these conditions, by ensuring that neither the amplifying or neutralizing system will be capable of supporting undesired oscillations.

I accomplish this result by the use of a damping element, such as a resistance, which is coupled to the system in such a manner that it is effective only in the parasitic oscillation circuits, and has no effect whatever in the useful load circuits. This damping element is used in addition to the neutralizing system or other means which may be employed for maintaining stability at the frequencies which the system is designed to amplify.

My invention possesses many other advantages, and has other objects which may be made more easily apparent from a consideration of several embodiments of my invention. For this purpose I have shown a few forms in the drawings accompanying and forming part of the present specification. I shall now proceed to describe these

forms in detail, which illustrate the general principles of my invention; but it is to be understood that this detailed description is not to be taken in a limiting sense, since the scope of my invention is best defined by the appended claims.

Referring to the drawings:

Figure 1 is a wiring diagram illustrating a tuned radio frequency amplifier system employing one of the neutralizing systems which have been proposed for preventing oscillations at the frequency to which the system is tuned, but in which the amplifier is prone to parasitic oscillations, as will be explained hereinafter;

Fig. 2 is the equivalent Wheatstone alternating current bridge of Fig. 1;

Figs. 3 and 4 are simplified diagrams illustrating the manner in which parasitic oscillations are formed in the circuits of Fig. 1;

Fig. 5 is a diagram showing the tuned neutralized amplifying circuit of Fig. 1 with the addition of my stabilizing system for suppressing parasitic oscillations;

Fig. 6 is a diagram of the equivalent Wheatstone alternating current bridge of Fig. 5;

Fig. 7 is a diagram more clearly showing the manner in which my stabilizing system acts to suppress parasitic oscillations;

Fig. 8 is a wiring diagram of an alternative form of my stabilizing system;

Fig. 9 is a diagram showing an application of my stabilizing system to the prevention of parasitic oscillations in a push-pull amplifier;

Fig. 10 is a diagram of a stabilizing system in combination with a neutralizing circuit in a push-pull amplifier; and

Fig. 11 is a simplified diagram for explaining the operation of the system shown in Fig. 10.

The manner in which parasitic oscillations are formed in amplifier circuits and the action of my invention in suppressing them may now be considered in detail.

Fig. 1 illustrates a tuned radio frequency amplifier of two stages incorporating one of the neutralizing systems which have been proposed for preventing oscillations at the frequency to which the system is tuned as an amplifier. Coils 20¹, 15 and 25 constitute the primary and secondary of a radio frequency transformer which is tuned to resonance at the frequency it is desired to amplify by capacitor 28. A portion of the potentials which are built up in the resonant system is impressed upon the grid 13 of the electronic emission amplifier 11. The coils 15 and 25, which form the secondary are usually made substantially equal and are connected at their center point E, to the cathode 12 of the amplifier 11, through the medium of ground connections 16 and 17. (A "C" battery may

circuit.) The variations in potential which are impressed between grid 13 and cathode 12 cause variations in the current in the anode circuit of the amplifier. This anode circuit includes the primary 18, of the succeeding 70 tuned radio frequency transformer. The second stage of amplification which includes the resonant circuit 79, 80 and 81, and amplifier 36, functions in a similar manner further to amplify the impulses. 75

If no provision were made for neutralizing the capacitive coupling 20 which exists between the grid 13, and anode 14 of the amplifier 11, energy would be fed back from the output circuit to the resonant input circuit and the system would oscillate at a frequency substantially the same as that to which the resonant circuit is tuned. It is possible that an amplifier of a single stage might be proportioned so that oscillations would not be formed, but when more than one stage is employed, or when the amplification is of more than a nominal amount, such oscillations are certain to be formed, unless means are taken to prevent their formation. 80 In the neutralizing system illustrated in Fig. 1 this is accomplished by the use of capacitor 24, which feeds energy from the output circuit back to the end of the input circuit opposite to the point at which the grid is connected. 85

Since the functioning of such a neutralizing system is well understood, it is only necessary to refer briefly to the equivalent Wheatstone alternate current bridge illustrated in Fig. 2. Here numeral 20 represents the grid-anode capacitance and 24 is the neutralizing capacitor as in Fig. 1. Numerals 15 and 25 designate the two sections of the secondary of the tuned radio frequency transformer and 28 designates the tuning capacitor, all as in Fig. 1. Numeral 20¹ represents the primary of the transformer and 18 represents the primary of the transformer of the succeeding stage. When

$$\frac{C_{20}}{C_{24}} = \frac{L_{25}}{L_{15}}$$

the bridge is balanced. If a potential is impressed across points A and B, points C and D will then be at equal potential. Vice versa, when a potential is impressed at C and D, points A and B will be at equal potential. A potential across C and D, therefore, does not cause any current to circulate in the resonant circuit 15-25-28. Since no current circulates in this circuit, there is no transfer of energy from coil 18, in the output circuit back to coil 20¹, of the preceding stage. The system is, therefore, neutralized against the transfer of energy from one stage back to the preceding stage. There is, however, a transfer of energy from the output side of each amplifying tube back to the input side of the same tube. The amount of regeneration

which may thus be produced depends upon the parallel opposing leakage inductance of 15 and 25. If a mutual inductance M_{15-25} of these coils were 100%, no potential would be applied to the grid as a result of the currents flowing from inductor 18, back through capacitors 20 and 24 to the coils 15 and 25; but when M_{15-25} is less than 100%, potentials will be applied to the grid and a certain amount of regeneration will result. However, so long as the bridge is balanced, no currents flow in the resonant circuit and the amount of regeneration is usually not sufficient to cause instability. In fact, it may be of advantage in reducing the losses in the system.

The bridge system shown in Fig. 2 is neutralized against the transfer of energy from a preceding stage to a succeeding stage as well as in the reverse direction. Currents which circulate in the resonant circuit 15—25—28, cause no flow of current in the inductor 18, since C and D are at equal potential when the bridge is balanced. Hence, no transfer of energy takes place from circuit 15—25—28 to circuit 79—80—81 in either direction so long as the bridge is balanced. This is the function of all the various neutralizing systems which have been proposed for preventing oscillations at the resonant frequency in tuned radio frequency amplifiers.

The above discussion deals only with the manner in which the neutralizing circuits serve to prevent oscillations at the frequency to which the system is tuned as an amplifier. It will now be shown that the addition of neutralizing circuits aggravates another condition of instability and causes the system to generate parasitic oscillations at a frequency which is dependent upon the parallel opposing leakage inductance of 15 and 25 and the stray capacitances to ground 26 and 27, of the various inductances, capacitors, wiring, etc., which comprise the amplifier and its associated circuits. The system has two degrees of freedom, one for the currents to be amplified which flow through coils 15 and 25 in series, as shown by arrows 38—38; and the other for currents flowing through the same coils in parallel as shown by the dotted arrows 39—39. It is the latter free period which leads to the formation of parasitic oscillations as will now be explained.

Fig. 3 shows the circuits of Fig. 1 with the parts rearranged to bring out the manner in which they combine to form the oscillatory circuits in which the parasitic oscillations are formed. For practical purposes, the system of Fig. 3 may be reduced to the circuits shown in Fig. 4. Numeral 89 represents the leakage inductance of coils 15 and 25 taken in parallel opposing. Numeral 90 is the net capacitance of the network comprising capacitors 26, 27 and 28. Numerals 18 and 88

are the leakage inductance and distributed capacitance of the primary of the succeeding stage. Numeral 91 is the grid-anode capacitance of the amplifier 11, plus capacitors 24 and 28, taken in series. This system constitutes an unneutralized amplifier stage tuned for frequencies which are usually well above those which the system is intended to amplify. It is, in fact, a Hartley oscillator, but with increased feed back. The manner in which oscillations are formed and sustained in such an unneutralized amplifier circuit is thoroughly explained in an article entitled, "The audion oscillator," by R. A. Heising, which was published in the Journal of the American Institute of Electrical Engineers, for April and May, 1920. The fundamental theory of oscillators is completely developed in this article and the reduction of radio-frequency amplifiers to the corresponding Hartley oscillator is thoroughly explained with circuit diagrams, reactance vs. frequency characteristics, and vector diagrams. It is shown in this article, in the discussion of Figs. 21 to 24 inclusive, how the usual, unneutralized, radio frequency amplifier stage is reduced to the Hartley oscillator. The grid-anode capacitance forms the capacitance of the oscillatory circuit, while the inductive reactances of the grid and anode oscillatory circuits, at a frequency slightly below resonance for the lower of the two, form the inductance of the oscillatory circuit. It is shown that the complete circuit will oscillate at a frequency slightly below the natural period of the circuit having the lower resonant frequency and that large changes in the grid-anode capacitance make very small changes in the frequency of the oscillations. This circuit will oscillate vigorously over a wide range of circuit constants and the oscillations are difficult to suppress.

The parasitic oscillations, the mode of formation of which is described above, are difficult to suppress even in a single tuned radio frequency stage, and are practically impossible to suppress by any ordinary methods, such as variations in circuit constants, in a multiple stage amplifier. The fact that the multiple stage amplifier may incorporate neutralizing means is of little avail in preventing parasitic oscillations, since one stage is coupled to another through stray capacitances, as indicated by 92 and 93 in Fig. 4. In fact, as explained above, the neutralizing circuit usually aggravates the situation rather than improves it.

As hereinbefore outlined, one object of my invention is to provide effective means of suppressing the parasitic oscillations which have hitherto rendered the above described type of neutralized radio frequency amplifier impracticable. This I accomplish by the method illustrated in Fig. 5, wherein capacitors

29 and 30, and resistor 31, have been added to the neutralized circuits of Fig. 1. We now have an alternating current Wheatstone bridge consisting of eight arms: 15 and 25, 5 29 and 30, 26 and 27 and finally 20 and 24. This differs very materially from the usual bridge of four arms. In order to balance the eight arm bridges, each of the three pairs of capacity arms must be adjusted to have 10 the same reactance ratio as the pair of inductance arms. In other words,

$$\frac{C_{29}}{C_{30}} = \frac{C_{26}}{C_{27}} = \frac{C_{20}}{C_{24}} = \frac{L_{25}}{L_{15}}$$

15 when the bridge is balanced. In practice, stray capacitances 26 and 27, are usually of small magnitude and so nearly balanced that they need not be taken into account, and the bridge reduces to six arms instead of eight. 20 When the bridge is balanced, points E and F, as well as points C and D, are at equal potential for currents circulating in the resonant circuit 15—25—28. Since E and F are at equal potential, the useful load currents 25 circulating in the resonant circuit induce no current in the resistor 31, and it, therefore, has no effect on the operation of the system as an amplifier. Also, since C and D are at equal potential, the neutralization system 30 remains undisturbed and exactly as before.

It will now be shown, however, that resistor 31 is coupled directly across points of high potential difference for the parasitic oscillations whose formation was described by the 35 aid of Figs. 3 and 4. This is brought out in Fig. 7 which is the same as Fig. 4 but with the addition of the parasitic suppression circuit 29—30—31. It will be seen that the resistor 31, which, as above shown, is connected across points of equal potential for the useful load currents, is coupled directly across points of high potential for the parasitic oscillations. This is due to the fact 40 that the load currents flow in series through coils 15 and 25, while the parasitic currents flow in parallel through the same coils. By suitably adjusting the value of resistor 31, it may be made to absorb so much energy 45 from the parasitic oscillation circuit that these oscillations are completely suppressed. It has been found in practice that for the usual radio frequency amplifier this value 50 is not at all critical. For example, in an amplifier designed for broadcast reception, in the band from 550 to 1500 kilocycles it 55 may be of any value between 300 and 2000 ohms. Capacitors 29 and 30, also may vary over a considerable range. For broadcast reception, values ranging from 30 to 50 micro-micro-farads are suitable. If capacitors 60 29 and 30 are made too small, the coupling between the resistor 31, and the circuit in which the parasitic oscillations are formed may not be sufficient to prevent such oscillations from forming. If too large, the main

resonant circuit may not tune to the highest frequencies which are to be amplified. Otherwise the limitations are very broad.

The particular location of the damping resistance so that it is effective in a parasitic circuit and ineffective in a useful circuit can be varied. For example, in Fig. 8 an arrangement is shown in which the damping element is inductively coupled to coils 15 and 25, rather than being capacitively coupled as in the circuits described above. In this case, a circuit including coils 34 and 35 and damping resistance 33, is coupled to both coils 15 and 25. The coupling to coil 15 is effected by a coil 34, and the coupling to coil 25 is effected by another coil 35, in series with coil 34. The arrangement is such that equal and opposite E. M. F.'s are induced in coils 34 and 35 for the load currents passing in series through coils 15 and 25, and consequently no damping current flows through resistance 33. However, for the parasitic currents which flow in parallel through coils 15 and 25, the E. M. F.'s induced in coils 34 and 35, are cumulative, and strong damping results for the parasitic oscillations.

In the two forms of my invention thus far described, there are only two stages of amplification; however, the damping scheme can be utilized with any number of stages. Furthermore, it is not limited to radio frequency systems. For example, serious parasitic oscillations often occur in connection with either radio or audio frequency "push-pull" amplifiers. In Fig. 9, I show an audio frequency push-pull amplifier system, utilizing two transformer coupled stages, in which my stabilizing scheme may be very advantageously used.

In this figure, each stage includes a pair 105 of tubes 40 and 41. The input circuit of tube 40, includes grid 46, coil 42, a grid bias battery 43, ground connections 44 and 45, and cathode 47. The output circuit includes anode 48, transformer primary 49, B battery 50, and cathode 47.

The input circuit and the output circuit of the other tube 41, have elements in common with the respective circuits of tube 40, as is now well known in connection with push-pull systems. Thus the input circuit of tube 41, includes grid 51, coil 52, battery 43, ground connections 44 and 45, and cathode 53. The output circuit includes anode 54, transformer primary 55, B battery 50 and cathode 53.

The incoming circuit 56, is shown as connected to the primary of an iron cored transformer 57, which is coupled to both coils 42 and 52. When a signaling impulse flows in circuit 56, the grids 46 and 51 are oppositely affected. Primary coils 49 and 55, however, are so arranged that their effect on the succeeding stage including coils 58 and 59, is cumulative.

This cursory review of push-pull amplifi- 130

cation is included here merely for the purpose of providing a foundation for the following explanation of the application of my invention to such systems. It is apparent that the 5 leakage inductances of coils 42 and 52, in parallel opposing, together with the stray capacities 26 and 27, indicated in dotted lines, form a parasitic oscillatory system similar to that described in connection with Fig. 1. 10 Oscillations in this system will deleteriously affect the operation of the audio-frequency system if not controlled or damped and may become so strong as to block the amplifier completed. By using a pair of series capacitors 15 60 and 61, I can provide a bridge 42-52-61-60 that operates as the bridge 15-25-30-29, of Fig. 5. Thus a resistance 20 63, can be connected between points of equi-potential so far as the load currents are concerned, but across points of large potential difference for the parasitic currents to be suppressed. Resistance 63 is for this purpose connected between coils 42 and 52, and between 25 capacities 60 and 61.

25 In the audio frequency system of Fig. 9, the damping system is shown in each stage, and only two stages are shown, feeding an outgoing circuit 66. However, it is apparent that the same scheme can be used for each 30 of any number of stages, and for radio frequency push-pull systems also. For radio frequency systems, the input circuits may be tuned, and the iron cores of the coupling transformers may be omitted. One form of 35 such a radio frequency push-pull system is shown in Fig. 10.

In that figure, the amplifier tubes 67 and 68, of each stage have input circuits that include coils 69 and 71 and output circuits including coils 70 and 72. The system operates just as that of Fig. 9, except that a tuning capacitor 73 may be provided, and that the couplings between stages are affected without the aid of iron-cored coils. As in the 45 prior systems described, leakage inductances and stray capacities cause parasitic oscillations which flow in parallel in coils 69 and 71. By providing a pair of series capacitors 74 and 75, across coils 69 and 71, which capacitors have the proper ratios to the inductances, a selective damping bridge is formed. A resistor 76 is connected across points E and F that are equipotential for the load currents, but which have a considerable potential difference for the parasitic currents.

50 In the form of the invention shown in Fig. 10, neutralizing circuits are also included. The neutralization for the grid-plate 55 capacitors 101 and 102 is affected by the aid of capacitors 77 and 78, forming with coils 69 and 71 and 70 and 72, and the other capacitances of the system, an alternating Wheatstone bridge having four inductive and eight capacitive arms as shown in Figure 11. Since 60 the transformers of a push-pull system are

usually made so that the two primaries and two secondaries are fully balanced, it is only necessary to balance each pair of capacities in order to have the entire bridge in balance. Thus, for a fully balanced system, $L_{69}=L_{71}$, $L_{70}=L_{72}$, $C_{101}=C_{102}$, $C_{77}=C_{78}$, $C_{74}=C_{75}$, and $C_{26}=C_{27}$.

70 In the following claims, the term "load current" is used to include those currents essential to the proper operation of the system, such for example as the currents to be amplified and the neutralizing currents, but not such currents as arise from parasitic oscillations at frequencies determined by the strap capacitances and leaking inductances of the system.

75 I claim:

1. In an amplifier, the combination of an electron discharge device having input and output electrodes, a tuned input circuit for 80 said device including inductance and capacity, one end of said inductance being connected to one of said input electrodes and an intermediate point on said inductance being connected to another of said input electrodes, a capacity connected in series between the other end of said inductance and one of 85 said output electrodes, an impedance shunting said input circuit, and a non-reactive circuit including a damping resistance and 90 connecting said intermediate point with a point on said impedance that is equi-potential therewith with respect to load currents in 95 said input circuit.

2. In an amplifier, the combination of an 100 electron discharge device having input and output electrodes, an input circuit connected to said input electrodes and including an input transformer, a pair of capacities in 105 series shunted across said transformer, and a non-reactive damping circuit connected between said capacities and to an intermediate point on 110 said transformer, said two capacities and the two portions of said transformer constituting a balanced Wheatstone bridge.

3. In an amplifier, the combination of an 115 electron discharge device having input and output electrodes, a tunable input circuit connected to said input electrodes and including an input transformer, a pair of capacities in 120 series shunted across said transformer, and a damping resistance connected between said capacities and to an intermediate point on said transformer, the points of connection of said resistance being equi-potential with respect to load currents in said input circuit.

4. In an amplifier, the combination of an 125 electron discharge device having input and output electrodes, an input circuit connected to said input electrodes and including an inductance, one end and an intermediate point of said inductance being connected to said input electrodes, a neutralizing capacity connected to the other end of said inductance and to one of said output electrodes, a pair 130

of capacities in series shunting said inductance, and a damping resistance connected to an intermediate point on said inductance and between said capacities.

5. In an amplifier, the combination of an electron discharge device having input and output electrodes, a tunable input circuit including an input inductance and a variable capacity, one end and the midpoint of said input inductance being connected to said input electrodes, a neutralizing capacity connecting the other end of said inductance and to one of said output electrodes, a pair of substantially equal capacities connected in series across said inductance and an aperiodic damping circuit connected to the midpoint of said inductance and between said capacities.
10. In an amplifier, the combination of an electron discharge device having input and output electrodes, a tunable input circuit including an input inductance and a variable capacity, one end and the midpoint of said input inductance being connected to said input electrodes, a neutralizing capacity connecting the other end of said inductance and to one of said output electrodes, a pair of substantially equal capacities connected in series across said inductance and an aperiodic damping circuit connected to the midpoint of said inductance and between said capacities.
15. In an amplifier, the combination of an electron discharge device having input and output electrodes, a tunable input circuit including an input inductance and a variable capacity, one end and the midpoint of said input inductance being connected to said input electrodes, a neutralizing capacity connecting the other end of said inductance and to one of said output electrodes, a pair of substantially equal capacities connected in series across said inductance and an aperiodic damping circuit connected to the midpoint of said inductance and between said capacities.
20. In an amplifier, the combination of a plurality of electron discharge devices having input electrodes, a common input circuit connected to said electrodes, a plurality of capacitors in series directly shunted across said input circuit, and aperiodic damping means connected between said capacitors and to an intermediate point on said input circuit, the points of connection of said damping means being equipotential with respect to useful load currents in said input circuit.
25. In an amplifier, the combination of a plurality of electron discharge devices having input and output electrodes, a common input circuit connected to said input electrodes, a reactive connection between the output electrode of each of said devices and the input electrode of the other of said devices, a plurality of capacitors in series directly shunted across said input circuit, and aperiodic damping means connected between said capacitors and to an intermediate point on said input circuit, the points of connection of said damping means being equipotential with respect to useful load currents in said input circuit.
30. In an amplifier, the combination of a plurality of electron discharge devices having input and output electrodes, a common input circuit connected to said input electrodes, a reactive connection between the output electrode of each of said devices and the input electrode of the other of said devices, a plurality of capacitors in series directly shunted across said input circuit, and aperiodic damping means connected between said capacitors and to an intermediate point on said input circuit, the points of connection of said damping means being equipotential with respect to useful load currents in said input circuit.
35. In testimony whereof I have hereunto set my hand.

HAROLD F. ELLIOTT.
